UNITED STATES PATENT OFFICE

122,611

DESIGN FOR A PORTABLE GRANDSTAND FRAME

Reinhold A. Uecker and David E. Beatty, Wauwatosa, and Lawrence C. Oertle, Milwaukee, Wis., assignors to Safway Steel Scaffolds Co. of Wisconsin, Wauwatosa, Wis., a corporation of Wisconsin

Application February 7, 1940, Serial No. 90,078

Term of patent 14 years

To all whom it may concern:

Be it known that we, Reinhold A. Uecker, David E. Beatty, and Lawrence C. Oertle, citizens of the United States of America and residents of Wauwatosa, Wauwatosa, and Milwaukee, respectively, in the county of Milwaukee and State of Wisconsin, have invented a new, original, and ornamental Design for Portable Grandstand Frame, of which the following is a specification, reference being had to the accompanying drawing, forming a part thereof.

In the drawing:

The single figure shows a perspective view of the portable grandstand frame showing our new design.

We claim:

The ornamental design for a portable grandstand frame as shown.

REINHOLD A. UECKER.
DAVID E. BEATTY.
LAWRENCE C. OERTLE.
